UNITED STATES PATENT OFFICE

143,160

DESIGN FOR A COMPUTER

Clarence A. Olson, Minneapolis, Minn.

Application June 9, 1945, Serial No. 119,989

Term of patent 3½ years

(Cl. D52—1)

To all whom it may concern:

Be it known that I, Clarence A. Olson, a citizen of the United States, residing at Minneapolis, in the county of Hennepin and State of Minnesota, have invented a new, original, and ornamental Design for a Computer, of which the following is a specification, reference being had to the accompanying drawing, forming part thereof.

Referring to the drawing:

Fig. 1 is a top plan view of a computer showing my new design;

Fig. 2 is a front elevational view; and
Fig. 3 is an end elevational view thereof.

I claim:

The ornamental design for a computer, substantially as shown.

CLARENCE A. OLSON.
